GARMENT HANGER

Robert M. Sprague, Pittsburgh, Pa.

Application July 23, 1948, Serial No. 40,311

14 Claims. (Cl. 223—94)

1

My invention relates generally to garment hangers, and it has reference in particular to collapsible garment hangers of the type such as may be worn in place in a garment.

Generally stated, it is an object of my invention to provide a garment hanger which is simple and inexpensive to manufacture, and is easy to install and use.

More specifically, it is an object of my invention to provide a collapsible hanger for a garment, having separable arms detachably secured within the garment, and which may be readily connected to provide a substantially rigid hanger.

Another object of my invention is to provide in a hanger for using telescopic arms which are hooked together vertically to provide a rigid integrated structure.

It is one object of my invention to provide in a collapsible garment hanger for supporting a hook support integral with one of the arms, and for connecting the other arm to said arm when it is desired to use the hanger.

An important object of my invention is to provide in a garment hanger for securing one portion of a pair of telescopic arms to the lining of the garment, and connecting the other portions to form a substantially rigid cantilever structure.

Yet another object of my invention is to provide for mounting a hook support integral with one of two telescopic hanger arms and for utilizing the mounting therefor for effecting connection with the other arm.

A yet further object of my invention is to provide for making a collapsible hanger having extensible arms which make a substantially rigid hooked connection with each other.

I also propose to provide for detachably securing a two-piece hanger in a garment by means of snap fasteners or the like so that the garment may be worn with the hanger positioned therein, and yet the hanger may be removed for cleaning purposes or the like.

Another important object of my invention is to provide an inexpensive collapsible garment hanger which may be worn inconspicuously in place in a garment, and yet readily detached from the garment.

Other objects will, in part be disclosed herein-after, and will in part be obvious.

In practising my invention in one of its forms, a hanger has separate arms comprising tubular members detachably secured to the lining of a coat or the like at the shoulders by means of snap fasteners and extensible rods telescopically posi-

2

tioned in the tubular members and having hooked end portions projecting towards each other. A connector rigidly supported on one hooked end portion has a socket for receiving the other hooked end portion to connect the rods when the hanger is in operating position. A support hook is pivotally mounted on the connector, and folds back along the rod on which the connector is supported, and when not in use.

For a more complete understanding of the nature and scope of my invention, reference may be made to the following detailed description, which may be read in connection with the accompanying drawing in which:

Fig. 1 is a partial front view of a coat or other garment, broken out in part, to show one application of a hanger embodying the features of my invention, in the collapsed or wearing position;

Fig. 2 is an enlarged, partially sectioned, view of a hanger embodying my invention, shown in the collapsed position in which the arms are separated, as the hanger is disposed when the coat is worn and the hanger is not in use;

Fig. 3 is an enlarged front elevational view broken away and partly in section, of the hanger shown in Fig. 2, with the rods extended and connected in operating relation as when the hanger is used to support the coat;

Fig. 4 is a sectional view along the line IV—IV of Fig. 3;

Fig. 5 is a front elevational view of a coat with a hanger embodying the invention, shown with the arms extended and connected in operating relation.

Fig. 6 is an enlarged partial view of a hanger embodying the invention in another of its forms; and

Fig. 7 is a partial front view in perspective of a portion of a hanger, showing one method of securing the hanger in a coat.

Referring particularly to Figs. 1 and 5 of the drawing, the reference numeral 10 may denote generally a hanger disposed to comprise spaced apart extensible arms 12 and 13, which may be detachably secured within the shoulder portions of a garment such as the coat 14. As shown in Fig. 1 the arms 12 and 13 may be separated and retracted when the hanger is not in use, such as when the coat is worn.

As shown in Fig. 3 it may be seen that the arms 12 and 13 of the hanger 10 may comprise body members 15 and 16, provided with extensible rods 17 and 18, normally positioned within the body members. The rods 17 and 18 may be withdrawn from the arms 12 and 13, and secured to-

gether by means of a connector 19, having support means such as a hook 20 mounted thereon for supporting the coat when the hanger is in use.

Referring to Figs. 2 and 3, it will be seen that the body members 15 and 16 of the arms 12 and 13 may comprise similar, elongated, hollow, or tubular body members having axial openings therein. Adjacent ends of the body members may be partially enclosed by means such as caps 24, having reduced openings 26 through which the rods pass. Similar caps 27 may be positioned on the remote ends of the body members after the rods are inserted therein, for retaining them therein and protecting the garment from the otherwise sharp ends of the body members. Detachable securing means such as snap fasteners 29 may be mounted adjacent the ends of the body members 15 and 16 for detachably securing the hanger to the coat or other garment. The male portions 29a of the fasteners may, for example, be soldered, welded, or otherwise secured to tabs 30, which may be mounted on the body members so that the male portions of the fasteners are positioned below the upper edges of the body members. The female or complementary portions of the fasteners may be sewed or otherwise secured to the lining of the coat.

The rods 17 and 18 may comprise, for example, similar lengths of relatively stiff spring steel, stainless steel, or other similar wire, or the like. They may have straight body portions 42 positioned within the body members of the arms 12 and 13, and having angularly related portions 45 projecting therefrom. Downwardly projecting hooked end portions 47 may be positioned at adjacent ends of the angularly related portions. The body portions 42 may be provided with enlarged end portions 44, comprising, for example sleeves or short lengths of tubing soldered or otherwise secured to the rods, and which engage and interfere with caps 24 and 27 to limit longitudinal movement of the rods.

In order to provide for connecting the rods 17 and 18 to form a substantially rigid structure, the connector 19 may be rigidly mounted on one of the hooked end portions, for example, the hooked end portion 47 of the rod 18. The connector 19 as shown in Figs. 2, 3 and 4, may comprise a substantially U-shaped plate or body having the hooked end portion 47 of the rod 18 secured therein at the bottom thereof, by soldering, welding, brazing, or the like. Transverse support means such as the rivet 50, may pass through the sides of the connector 19, to provide a socket or opening between the rivet and the hooked end portion 47 of the rod 18, for loosely receiving the hooked end portion 47 of the rod 17, whereby the arms 12 and 13 may be connected. By having both the end portion 47 of the rod 17 and the adjacent portion of the angularly related portion 45 thereof, recessed between the upstanding sides of the connector plate 19, a substantially rigid lateral connection between the arms may be obtained.

The hook support 20 may be pivotally secured to the connector 19 by the rivet 50. As shown, the support 20 may be foldable, comprising for example, hinged portions 20a and 20b connected by a pin 20c. An ear 51 may be provided on the portion 20b to interfere with the portion 20a and prevent the hook from opening beyond the desired amount. Snap fasteners 52 and 53 may be secured to the angularly related end portion 45 of the rod 17, and to the connector 19 to secure

them in the garment 14 when the hanger is not in use.

Referring to Figure 6 of the drawing, it will be seen that in another embodiment of the invention rods 17' and 18' may be provided with angularly related end portions 45' which are bent downwards, instead of upwards as shown in Figs. 2 and 3. The angularly related portions 45' may be provided with hooked end portions 47' at adjacent ends, which may be bent upwardly. A connector 19' may be rigidly secured to one hooked end portion, for example, the portion 47' of the rod 17', and a support hook 20' which may be of one piece, instead of folding as in Figs. 2 and 3, may be mounted on the connector 19' by means of a rivet 50'. The rivet 50' may be so located that it provides an opening for receiving loosely the hooked end portion 47' of the rod 18'. The hooked end portion 47' of the rod 18' may be provided with a reentrant bent end portion 49 at the upper end disposed to engage the rivet 50' and prevent the hooked end portion 47' of the rod 18' from sliding downwardly out of the opening in the connector 19' when the hanger is being used.

Referring to Figure 7 of the drawing, it will be seen that the body members of the arms 12 and 13 may be positioned in the shoulder portion of the coat 14 by other means than the snap fasteners shown in Figs. 2 and 3. For example, a body member 15 of the type described in detail in connection with Figs. 2 and 3, may be positioned in a longitudinal pocket 55 in a strip of material 56, formed by running a seam down the strip adjacent a longitudinal fold therein. The strip of material may then be secured to the lining of the garment by sewing it in place, using snap fasteners as shown in Figs. 2 and 3, or other known fastening means such as zippers, or the like. Instead of securing snap fasteners on the exposed or outer surface of the lining of the coat, the snap fasteners may, with any of the hanger constructions, be secured to the inner side of the lining, between the lining and the coat, and a slot or buttonhole may be cut in the lining to permit the insertion of the arms between the lining and the coat, whereupon they may be secured to the lining by snapping the fasteners in the usual manner.

From the above description and the accompanying drawing it will be realized that I have provided a hanger which is both simple to operate and manufacture, and is reliable and effective in use. A hanger embodying the features of my invention lends itself readily to mass production methods, and may be made either from tubular and rod members, or pressed or stamped out from sheet metal, as desired.

When the hanger is assembled, the end caps limit longitudinal movement of the rods, and retains them within the body members, so that they cannot become detached and lost. The hanger may be readily put into use from the collapsed condition, and provides a light, compact and yet rigid structure. Connection and disconnection of the extensible arms is easily made, and the hanger when retracted is so compact that it may be readily worn within even the lightest of summer garments, for example, without being conspicuous or inconvenient.

Since different embodiments of the invention may be made without departing from the spirit or scope of the invention, it is intended that all the matter contained in the foregoing description or shown in the accompanying drawing shall

be considered as illustrative, and not in a limiting sense.

I claim as my invention:

1. A hanger comprising, a pair of arms, each of said arms comprising a pair of telescoping members, connecting means integral with one of the members of one of said arms, said connecting means providing a rigid hooked connection with one of the members of the other arm, and support means mounted on said connecting means.

2. In a hanger for a garment, a pair of extensible arm members, one of said arm members having an angularly related end portion at one end, fastening means on said arm members disposed to attach them to the garment, a connector supported by the other of the arm members having a corresponding angularly related socket at one end disposed to receive the angularly related end portion of the said one arm member, and a hook support mounted on the connector.

3. A hanger disposed to be detachably secured to a garment comprising, a pair of extensible arms having rigid hooked end portions and fastening means disposed to effect a detachable connection with the garment, and a connector secured to the hooked end portion of one arm, said connector having a socket to receive the hooked end portion of the other arm.

4. A hanger comprising, a pair of extensible arms, a connector integral with one of said arms having an angularly related socket, an angularly related end portion on the other of said arms disposed to effect a hooked connection in the socket with said one arm, and a hook support mounted on the connector.

5. A hanger comprising, a pair of arms, means on each of said arms for detachably securing them to a garment, a connector secured to one arm and having a socket to receive a portion of the other arm, and a hook support pivotally connected to the connector.

6. A hanger disposed to be worn in a garment comprising, a pair of arms having angularly related end portions and fastening means disposed to detachably secure the arms within the garment, a connector for said arms mounted on the angularly related end portion of one of said arms and having an angularly related socket disposed to receive the angularly related end portion of the other arm, and a support hook secured to the connector.

7. A hanger comprising, a pair of arms having substantially vertical angularly related end portions and means on the arms to secure them in a garment, a connector mounted on the end portion of one of the arms having a substantially vertical socket to receive the end portion of the other arm, and a hook pivotally supported on the arm having the connector thereon.

8. In a hanger, a pair of arms comprising telescopic members, a connector secured to one member of one of said arms having a socket to receive a portion of one of the members of the other arm, and a hook pivotally mounted on the connector.

9. A hanger comprising, a pair of tubular members having fastening means for detachably securing them in a garment, rod members telescopically positioned in the tubular members and having hooked end portions on adjacent ends,

a connector secured rigidly to one of the hooked end portions and having a socket to receive the other hooked end portion, and a hook support pivotally mounted on the connector.

10. In a hanger, a pair of tubular arms, a rod telescopically mounted in each of the arms, said rods having downwardly extending hooked end portions projecting from adjacent ends of the arms, a connector comprising a substantially U-shaped member having the hooked end portion of one rod rigidly secured therein, a hook, and transverse support means pivotally supporting the hook on the connector, said support means being disposed to provide a socket in the connector for the hooked end portion of the other rod.

11. A hanger for supporting a garment comprising, a pair of tubular body members provided with detachable securing means disposed to secure them in spaced relation in the shoulder portion of the garment, longitudinally extensible rod members telescopically positioned within said body members and provided with angularly related end portions on adjacent ends, a connector plate secured rigidly to the end portion of one of the rod members and disposed to receive the end portion of the other rod member, and a hook mounted on the connector plate to support the hanger.

12. In a hanger for a garment, a pair of arms comprising tubular body portions having extensible rod members telescopically mounted therein, a connector secured to one rod member disposed to effect a hooked connection with the other rod member, a hook supported on the connector, and detachable securing means supported by the body members and rod members disposed to detachably secure them in predetermined relation within the shoulder portions of the garment.

13. A garment hanger comprising, a pair of extensible arms having hooked end portions at adjacent ends, a connector rigidly secured on one end portion and having a socket disposed to detachably receive the other end portion, and a folding hook support pivotally mounted on said connector.

14. A hanger comprising, a pair of tubular arms having snap fasteners thereon to detachably secure them in the shoulder portions of a garment, said arms having partially enclosed ends disposed adjacent each other, extensible rods mounted in the arms, said rods having hooked end portions projecting through the partially enclosed ends and enlarged end portions disposed within the arms, a connector mounted rigidly on one hooked end portion and having a socket disposed to receive the other end portion, and a folding hook pivotally mounted on the connector.
